CAID H. PECK, OF ATHENS, PENNSYLVANIA, ASSIGNOR TO INGERSOLL-RAND COMPANY, OF NEW YORK, N. Y., A CORPORATION OF NEW JERSEY.

FLUID-PRESSURE-OPERATED TOOL.

1,079,682.

Specification of Letters Patent. Patented Nov. 25, 1913.

Application filed April 13, 1912. Serial No. 690,580.

To all whom it may concern:

Be it known that I, CAID H. PECK, a citizen of the United States, and resident of Athens, in the county of Bradford and State 5 of Pennsylvania, have invented a new and useful Improvement in Fluid-Pressure-Operated Tools, of which the following is a specification.

This invention relates to fluid pressure 10 operated tools and has for its object to provide a novel and simple oiling device for a tool of this character having a telescope feed through which the motive fluid is fed to the tool piston, said device being arranged to 15 automatically and effectively lubricate the tool by supplying oil thereto in small quantities.

The oiler is herein shown and described in 20 connection with a telescope feed pneumatic hammer drill but it is to be understood that the oiler may be used in connection with telescope feed tools of various types without departing from the spirit and scope of my invention.

25 A practical embodiment of my invention is represented in the accompanying drawings, in which—

Figure 1 represents the tool in longitudinal central section taken in one plane, 30 with my improved oiler applied thereto, Fig. 2 is a similar view taken in a plane at right angles to that shown in Fig. 1, Fig. 3 is an enlarged cross section taken in the plane of the line A—A of Fig. 1, and Figs. 4, 5 and 35 6 are, respectively, front end, side, and rear end views of the oiler tube, a portion of the absorbent blanket being broken away in Fig. 5 to show the perforations in the tube.

The tool cylinder is denoted by 1 and its 40 piston by 2. The telescope feed for the tool comprises an inner fixed hollow feed piston 3 and an outer hollow feed cylinder 4 slidably mounted thereon. The feed piston 3 is spaced from the feed cylinder 4 except at 45 its front and rear ends, the rear end of the feed piston having a head 5 which loosely fits the bore of the cylinder and the front end of the feed cylinder having a fluid tight packing 6 which snugly embraces the feed 50 piston.

The feed cylinder has a motive fluid inlet 7 near its front end and the feed piston has a motive fluid inlet 8 near its rear end whereby the motive fluid may be fed to the tool 55 piston 2 through the bore of the feed piston

3. The motive fluid reaches the space 9 between the closed rear end of the feed piston 3 and the closed rear end of the feed cylinder 4 by escaping past the feed piston head 5.

The oiler which is located in the telescope feed comprises a perforated tube 10 having a screw threaded head 11 at its rear end and surrounded by an absorbent blanket 12 of tubular wicking or other suitable material. This tube is located in the forward portion of the bore of the feed piston 3, its head 11 having a screw threaded engagement with the walls of the bore and its forward end being held in engagement with the front end of the said bore thereby forming an annular oil chamber 13 surrounding the tube and absorbent blanket. The filling hole for this oil chamber is denoted by 14 and may be closed by a removable plug 15. A passage 16 leads from the front end of 75 the bore of the fixed feed piston 3 to the tool piston 2 for supplying motive fluid thereto for operating the same.

In operation, the motive fluid will pass 80 from the inlet 7 rearwardly in the space between the fixed feed piston and extensible feed cylinder to the fluid inlet 8 in the feed piston and also past the head 5 into the space 9 for feeding the tool to its work. The motive fluid will pass forwardly 85 through the bore of the feed piston 3 and the bore of the tube 10 into the passage 16 and from thence to the tool piston 2. This motive fluid under pressure will also pass through the perforations in the tube 10 and 90 through the blanket 12 into the oil chamber 13. When the supply of motive fluid is cut off for stopping the tool, the motive fluid under pressure in the oil chamber 13 will escape back through the absorbent blanket 95 12 and perforations in the tube 10 into the bore of said tube and will carry along with it a sufficient amount of oil to properly 100 lubricate the tool. When the tool is again started up, this oil will be carried forwardly 100 to the tool.

It is evident that changes might be resort- 105 ed to in the form, construction and arrangement of the several parts without departing from the spirit and scope of my invention; hence I do not wish to limit myself strictly to the structure herein set forth, but

What I claim is—

1. A telescope feed pressure fluid operated tool including an oiler located within the 110

telescope feed for supplying oil to the tool and means for feeding the pressure fluid to the tool through the oiler.

2. A telescope feed pressure fluid operated tool including a hollow feed piston, a feed cylinder and an oiler located in the feed piston for supplying oil to the tool and means for feeding the pressure fluid to the tool through the oiler.

10 3. A telescope feed pressure fluid operated tool including a fixed hollow feed piston, an extensible feed cylinder and an oiler located within the fixed feed piston for supplying oil to the tool and means for feeding the pressure fluid to the tool through the oiler.

4. A telescope feed pressure fluid operated tool including a fixed hollow feed piston, an extensible feed cylinder and an oiler comprising a perforated tube in the bore of the piston having a surrounding oil chamber, through which tube the motive fluid passes to the tool piston.

5. A telescope feed pressure fluid operated tool including a fixed hollow feed piston, an extensible feed cylinder and an oiler comprising a perforated tube in the bore of the piston having a surrounding oil chamber, through which tube the motive fluid passes

to the tool piston, and a blanket of absorbent material surrounding said tube.

6. A telescope feed pressure fluid operated tool including a hollow feed piston, a feed cylinder, and an oiler comprising a perforated tube provided with a head having a screw threaded engagement with the inner walls of the feed piston and its front end engaging the front end of the bore of the piston to form an oil chamber.

7. A telescope feed pressure fluid operated tool including a hollow feed piston, a feed cylinder, and an oiler comprising a perforated tube provided with a head having a screw threaded engagement with the inner walls of the feed cylinder and its front end engaging the front end of the bore of the piston to form an oil chamber, and a blanket of absorbent material surrounding the tube.

In testimony, that I claim the foregoing as my invention, I have signed my name in presence of two witnesses, this tenth day of April 1912.

CAID H. PECK.
